CLAIM

The ornamental design for a cleaning applicator with a swivel handle, as shown and described.

DESCRIPTION

FIG. 1 is a perspective view of a cleaning applicator with a swivel handle, showing my new design;

FIG. 2 is a top plan view thereof;

FIG. 3 is a front elevational view thereof;

FIG. 4 is a bottom plan view thereof;

FIG. 5 is a rear elevational view thereof;

FIG. 6 is a side elevational view thereof;

FIG. 7 is a perspective view thereof, shown with the handle in a partially opened position.

FIG. 7
